MULTIPLE BAND KNIFE MACHINE

Nicholas Marcalus, West Englewood, N. J.

Application May 26, 1952, Serial No. 289,959

9 Claims. (Cl. 164—35)

One of the objects of my invention is to provide a machine whereby products, for instance, paper rolls and the like may be severed in a manner to form relatively short rolls.

Another object of my invention is to provide a machine of the foregoing described character which may be equipped with means whereby wrappers are conveniently applied to the rolls.

A further object of my invention is to provide a machine of the foregoing described character in which endless cutting bands are employed for severing the major rolls and which are arranged in a manner to form a relatively short and compact structure.

An important object of my invention is to provide a machine of the foregoing described character which is simple in construction, durable in use, efficient in operation, economical in maintenance, and which lends itself to high productivity with respect to the forming of minor rolls from a supply roll.

With the above and other objects in view, as will hereinafter appear, my invention consists in the combination and arrangement of parts hereinafter set forth and illustrated in the accompanying drawings, from which the several features of the invention and the advantages attained thereby will be readily understood by those skilled in the art.

Referring to the drawings wherein like reference characters designate like parts throughout the several views:

Figure 1 is a side elevation, partly broken away, of my invention.

Figure 2 is a top plan view of the invention, the upper platform being broken away.

Figure 3 is a detail longitudinal sectional view of a portion of the front end of the machine.

Figure 4 is a diagrammatic transverse view illustrating the relationship of the cutting bands with respect to the conveyor and retaining belts.

Figure 5 is a view similar to Figure 3 but diagrammatically illustrating automatic means for feeding the wrappers into position for wrapping about the products.

Figure 6 is a diagrammatic front elevation of the structure disclosed in Figure 5.

As illustrated in Figures 1 to 4, inclusive, of the drawings, the machine is provided with a base 10 on which is secured front and rear pairs of frame members or uprights 11 and 12, the upper end sections of the uprights having secured thereto spaced upper and lower platforms 13 and 14, respectively. Secured between the platforms are vertical adjustable bearings 15 disposed above bearings 16 carried by the base, the bearings 15 and 16 having rotatably mounted thereon pulleys 17 and 18, respectively, disposed in paired relation one above the other. The lower platform 14 is relatively narrow and extends diagonally from one pair of said uprights to the other and between knife sections or runs 19 of endless cutting bands 20, each of the latter being trained about an upper and lower pulley as clearly illustrated in Figure 1 of the drawings. The bearings 16 are also provided with belt pulleys 21 for unitary rotation with the pulleys 18 and are each

2

connected to a motor 22 by a belt 23 or the like whereby the bands are individually driven.

Secured to the base 10, prejacent and postjacent the standards 12 and 13, are front and rear bearing standards 24 and 25 in which are journaled the ends of transverse shafts 26 and 27, respectively. Shafts 26 and 27 are provided with sprockets about which are trained endless sprocket chains 28 constituting a conveyor, said chains being laterally spaced relative to each other with pairs of flights 29 for accommodating therebetween products 30, disposed on the conveyor; one example of the products being relatively long paper rolls from which relatively short rolls are formed, for instance, rolls of toilet paper and the like and which long rolls are previously compressed to ovate shape to conserve shipping space. The standards 24 have secured thereto rearwardly disposed bearing brackets 31 in which are journaled the ends of a shaft 32 while the standards 25 have journaled therein the ends of a similar shaft 33 superjacent the shaft 27. The shafts 32 and 33 are provided with pulleys about which are trained spaced endless retaining belts 34 disposed above the chains 28 of the conveyor, the belts 34 functioning to maintain the products 30 between pairs of flights 29 on the uppermost run of the conveyor as illustrated in Figure 1 of the drawings.

For effecting operation of the chains 28 and the belts 34, a motor 35 is provided which is connected to and operates a speed reduction unit 36, the latter being provided with a sprocket 37 connected to a sprocket 38, fixed to one of a pair of relatively rotatable sections of a jack-shaft 39, by means of a chain 40. The jack-shaft is mounted in bearings 41 disposed beneath the conveyor and adjacent the standards 25 and has fixed to its other section a sprocket 42 connected to a sprocket 43, fixed to shaft 33, by means of a chain 44. A one-revolution clutch 45 connects the sections of the jack-shaft together and serves to effect unitary rotation thereof upon operation of the clutch as hereinafter made apparent. The shafts 27 and 33 are provided with meshing spur gears 46 for operating the chains 28 and belts 34 in unison and also, as a consequence, for effecting rotation of the shafts 26 and 32.

The base has mounted therein a transverse shaft 48 having fixed thereto one end of a treadle 49, the opposite end of the treadle extending beyond the front of the machine for actuation by an operator. The shaft 48 has secured thereto an upwardly extending clutch operating arm 50, the upper end of which is provided with a spring-pressed finger 51 for engaging an arm 52 of the clutch to effect operation of the latter, it being understood that when the treadle 49 is operated, the arm 50 effects tripping of the clutch arm 52 with the result that the sections of the jack-shaft 39 are operated in unison during one revolution of the clutch thus intermittently advancing the uppermost chain runs and the lowermost belt runs towards the rear of the machine.

From the foregoing and with particular reference to Figure 2 of the drawings, it will be noted that the knife sections 10 operate between pairs of chain and belt runs and are spaced with respect to each other and are unilaterally offset in successive order relative to each adjacent pair of the knife sections whereby the knife sections are operable between chain and belt runs of different paired relation. This arrangement enables the products to be severed into relatively short lengths, the transverse arrangement of the chains, belts, and cutting bands being diagrammatically illustrated in Figure 4 of the drawings.

In order that each of the rolls 30 may be provided with a wrapper W, previous to being severed by the knife sections 19, the standards 24 and brackets 31, immediately above the conveyor, have journaled therethrough the ends of actuating rods 53. The rods are provided, be-

tween the standards and the brackets, with front and rear plates 54 for folding a wrapper, deposited on the upper runs of the chains, about the roll. Coincident ends of the rods have fixed thereto sprockets 55, over which are trained chain sections 56 for operating the sprockets whereby the plates are actuated from their open or upright positions, as shown in dotted lines in Figure 3, to folded or horizontal positions as shown in full lines, the rear plate being disposed above the front plate. The ends of each chain section 56 are secured to the base of a spring 57 and to an arm 58, fixed to the shaft 48, by means of a rod 59, whereby, operation of the treadle 49 serves to actuate the plates in the foregoing described manner.

Secured between the uprights 11 and the brackets 31, above the belts 34, is a wrapper receptacle or holder 60 in which the wrappers W are contained for withdrawal and deposit onto the conveyor and which receptacle is provided with an open front end and bottom and rear walls 61 and 62, respectively. A wrapper retainer 63 is secured in sliding engagement with the rear wall 62 and has its upper end provided with an angled end section overlying the rear ends of the wrappers W. The ends of the angled end section are equipped with blocks in which are secured pins, one of which is illustrated at 64, having their lower ends relatively sharp and penetrating a plurality of the uppermost wrappers for a purpose hereinafter more fully described.

An adhesive distributor overlies the wrappers W and comprises a reservoir 65 formed with a pair of forwardly extending arms 66 fixed to a supporting shaft 67 journaled in the brackets 31 and on which shaft is loosely mounted a pair of relatively fixed sprockets 68. The rear end of the reservoir 65 is provided with an adhesive applying roller or applicator 69 constructed of suitable material, for instance, rubber, formed about and fixed to a drive shaft 70. The roller 69 functions to apply adhesive to the rear marginal area of the uppermost wrapper W disposed immediately subjacent the reservoir. The roller extends through an opening formed in the bottom wall of the reservoir and is engaged by a distributor plate 71 adjustably secured to the bottom wall by means of screws extending through elongated apertures provided in the plate. The face of the plate, which engages the roller, is slotted, the slots being of a width and depth to permit a desired quantity of the adhesive A, contained in the reservoir, to be distributed by the roller onto the uppermost wrapper W through the opening upon rotation of the roller. The shaft 70 of the roller is provided with a sprocket 72 connected to one of the pair of sprockets 68 by means of a chain 73, the other sprocket of the pair being connected to a sprocket 74 by means of a chain 75. The sprocket 74 is fixed to the shaft 32 whereby the roller 69 is rotated when the retaining belts are operated. Also fixed to the shaft 32 is a cam 76 for operating a cam arm 77 fixed to the shaft 67 and which functions to raise and lower the rear end of the reservoir and roller out of and into engagement with the wrappers W.

In operation, assuming that plates 54 to be in open position and the roller 69 is disposed out of engagement with the uppermost wrapper which has previously been supplied with adhesive, the uppermost wrapper is grasped by the fingers of the operator and moved outwardly from the receptacle 60 and positioned upon the upper run of the conveyor between a pair of the flights and the plates 54 as illustrated in dotted lines in Figure 3. As the uppermost wrapper is thus withdrawn, the rear corners are ruptured by the pins 64 to effect release of the wrapper thus permitting the weight of the retainer to insure further penetration of the pins into another of the uppermost remaining wrappers for holding the latter during application of adhesive. When the wrapper has thus been disposed on the conveyor, a roll 30 is disposed within the wrapper and the treadle operated to actuate the plates to their folded positions as illustrated in full lines in Figure 3, thus enfolding and sealing the roll within the wrapper.

When the treadle is operated, the clutch functions to effect operation of the conveyor and the belts and resultant lowering of the adhesive roller into engagement with the uppermost wrapper for applying adhesive thereto. As the conveyor advances, the treadle is released to permit the plates to return to their open positions while the roll, which is now enfolded in the wrapper, is conveyed into engagement with the lower runs of the belts and retained on the chains between the flights. As the conveyor and belts advance, the rolls are successively severed by the knife sections into relatively short lengths, thus, forming the toilet paper rolls or packs.

As diagrammatically illustrated in Figures 5 and 6 of the drawings, automatic mechanism may be employed for feeding the wrappers W from the receptacle 60 into position on the conveyor for wrapping about the rolls 30. The mechanism comprises a pair of arms 80 each formed at its upper end with an angularly disposed section and with a longitudinally extending slot or track 81 terminating in a seat 82 in the section. The slots 81 have mounted therein flange rollers 83 journaled on the ends of a transverse hollow shaft 84 connected by means of a flexible tube 85 to a negative source of pressure. The hollow shaft 84 has pivotally connected thereto and in communication therewith depending conduits, the lower ends of which carry vacuum cups 86 for engaging the uppermost wrapper for a purpose hereinafter more fully described. The lower ends of the arms 80 are connected together and provided with trunnions 87 journaled in the standards 24 and on which are loosely mounted pairs of relatively fixed sprockets 88, one sprocket of each pair being connected to a similar sprocket 89, mounted on the upper end of each arm, by a chain 90 which is provided with a dog 91. The other sprocket of each pair 88 is connected to one of a pair of sprockets 92 fixed to a shaft 93 also journaled in the standards 24. The shaft 93 has one end provided with a spur gear 94 meshing with a spur gear 95 loosely mounted on a stub shaft 96 carried by one of the standards 24. The spur gear is fixed to a sprocket 97 also loosely mounted on the stub shaft and connected with a sprocket 98, fixed on the shaft 26, by means of a chain 99. One of the trunnions 87 has fixed thereto the upper end of a cam arm 100, the lower end of which is provided with a roller 101 engaging a cam 102 mounted on the shaft 26 of the conveyor. In operation, assuming the cups 86 are in engagement with the uppermost wrapper as disclosed in full lines in Figures 5 and 6, and the conveyor shaft 26 is being rotated, the cam 102 serves to pivot and raise the arms 80 towards a vertical position and away from the receptacle 60 and with the chains 90 being operated through the sprocket and chain assembly heretofore described. As the arms 80 are thus rotated, the uppermost wrapper will be detached from the other wrappers and moved outwardly from the receptacle. As the arms 80 continue to move away from the receptacle, the hollow shaft 84 will be engaged by the spring fingers 103 fixed to the brackets 31 and force the rollers 83 out of the seats 82, whereupon the shaft 84 and rollers 83 will be gravitated downwardly to the lower ends of the arms 80 and thus carry the wrapper downwardly. This action results in the wrapper being completely withdrawn from the receptacle and deposited upon the conveyor and between the plates 54 as shown in dotted lines in Figure 5. When the wrapper has thus been positioned, a valve (not shown), connected between the cups 86 and the source of negative pressure, operates to break the pressure and release the front ends of the wrapper from the cups whereupon a roll of paper may be placed within the wrapper and between the plates 54. When the arms 80 have been operated in the foregoing described manner and assume the position illustrated in dotted lines in Figure 5, the dogs 91, carried by the chains 90, engage the outer projecting ends of the shaft 93 and move the latter upwardly towards the upper ends of the arms and position the rollers within the seats 82 as the arms are lowered by the action of the cam to per-

mit engagement of the cups 86 with the next uppermost wrapper for shifting the latter to the conveyor in the foregoing described manner.

From the foregoing it will be apparent that my invention provides a relatively simple and compact machine wherein the use of endless cutting bands for the severing of major rolls into short minor rolls is permitted due to arrangement of the bands with respect to the conveyor and retaining means.

Without further elaboration the foregoing will so fully explain the invention that others may, by applying current knowledge, readily adapt the same for use under various conditions of service. Moreover, it is not indispensable that all the features of the invention be used conjointly since they may be employed advantageously in various combinations and subcombinations.

It is obvious that the invention is not confined to the herein described use therefor as it may be utilized for any purpose to which it is adaptable. It is therefore to be understood that the invention is not limited to the specific construction as illustrated and described as the same is only illustrative of the principles of operation, which are capable of extended application in various forms and the invention comprehends all construction within the scope of the appended claims.

What I claim is:

1. In apparatus for transversely severing long paper rolls to produce short paper rolls, conveyor means having a plurality of spaced longitudinal runs; and cutting mechanism having a plurality of endless cutting bands each defining a pair of knife sections operable between pairs of said runs and being longitudinally spaced and unilaterally offset with respect to the adjacent pair of sections and with the latter operable between the closest runs unilaterally of a different paired relation, whereby paper rolls carried by said means are transversely severed by each pair of said sections successively.

2. In apparatus for transversely severing long paper rolls to produce short paper rolls, conveyor means having a plurality of spaced longitudinal runs; and cutting mechanism having a plurality of endless cutting bands each defining a pair of knife sections operable between pairs of said runs, said pairs being longitudinally spaced and unilaterally offset in successive order with respect to each adjacent pair of sections and with the latter operable between the closest runs unilaterally of a different paired relation whereby paper rolls carried by said means are transversely severed by each pair of said sections successively.

3. In apparatus for transversely severing long paper rolls to provide short paper rolls, conveyor means having a plurality of spaced longitudinal runs; cutting mechanism having a plurality of endless cutting bands each defining a pair of knife sections operable between pairs of said runs and being longitudinally spaced and unilaterally offset with respect to the adjacent pair of sections and with the latter operable between the closest runs unilaterally of a different paired relation, whereby paper rolls carried by said means are transversely severed by each pair of said sections successively, and retaining means coacting with said conveyor means for retaining paper rolls thereon during the severing.

4. In apparatus for transversely severing long paper rolls to produce short paper rolls, conveyor means having a plurality of spaced longitudinal runs; cutting mechanism having a plurality of endless cutting bands each defining a pair of knife sections operable between pairs of said runs and being longitudinally spaced and unilaterally offset with respect to the adjacent pair of sections and with the latter operable between the closest runs unilaterally of a different paired relation, whereby paper rolls carried by said means are transversely severed by each pair of said sections successively, retaining means coacting with said conveyor means for retaining paper rolls thereon during the severing, and means for

operating said conveyor means and said retaining means in unison.

5. In apparatus for transversely severing long paper rolls to produce short paper rolls, conveyor means having a plurality of spaced longitudinal runs; cutting mechanism having a plurality of endless cutting bands each defining a pair of knife sections operable between pairs of said runs and being longitudinally spaced and unilaterally offset with respect to the adjacent pair of sections and with the latter operable between the closest runs unilaterally of a different paired relation, whereby paper rolls carried by said means are transversely severed by each pair of said sections successively, and means for operating said conveyor means whereby paper rolls are advanced through said sections.

6. In apparatus for transversely severing long paper rolls to produce short paper rolls, conveyor means having a plurality of spaced runs; cutting mechanism having a plurality of endless cutting bands each operable between the runs of each of two pairs of said runs and being longitudinally spaced and unilaterally offset with respect to an adjacent band and with the latter operable between the closest runs unilaterally of a different paired relation, whereby paper rolls carried by said means are severed by each of said bands successively.

7. The structure of claim 6 as set forth and defined therein including, retaining means coacting with said conveyor means for retaining paper rolls thereon during severing.

8. In apparatus for transversely severing long paper rolls to produce short paper rolls, an endless conveyor having a plurality of spaced substantially horizontally disposed longitudinal runs equipped with transverse flights for securing rolls of paper crosswise upon said runs for movement with said runs, hold-down means disposed above said conveyor and having a plurality of spaced substantially horizontally disposed longitudinal runs superjacent said first mentioned runs and coacting with the latter and said flights for maintaining said rolls on said first mentioned runs during longitudinal travel of the latter, cutting mechanism having a plurality of endless cutting bands each defining a pair of knife sections disposed in substantial verticality and with each section operable between a pair of runs of said conveyor and said hold-down means, said pairs of said knife sections being longitudinally spaced and unilaterally offset in successive order with respect to each adjacent pair of knife sections and with the latter operable between the closest runs unilaterally of a different pair of said conveyor and said hold-down means whereby long paper rolls carried between flights by said conveyor are transversely severed by each pair of said knife sections, successively.

9. The structure as set forth and defined in claim 8 including, upper and lower groups of pulleys disposed above and below said hold-down means and said conveyor, respectively, and with each of said bands being trained about a pulley of each of said groups, the pulleys of one group being movable away from the pulleys of the other group to maintain said knife sections in a taut condition for severing said rolls and power means connected to one of said groups of pulleys for effecting operation of said bands between said runs.
